DESIGN FOR A BICYCLE CRANK

George S. Lewis, Evanston, Ill.

Application October 19, 1940, Serial No. 95,948

Term of patent 14 years

To all whom it may concern:

Be it known that I, George S. Lewis, a citizen of the United States, residing at Evanston, county of Cook, and State of Illinois, have invented a new, original, and ornamental Design for a Bicycle Crank, of which the following is a specification, reference being had to the accompanying drawing, forming a part thereof, in which:

Figure 1 is a top plan view of a bicycle crank, showing my new design; and Fig. 2, an end elevational view.

I claim:

The ornamental design for a bicycle crank, as shown.

GEORGE S. LEWIS.
